EDGE GUIDE FOR SEWING MACHINES

Filed Feb. 16, 1951

UNITED STATES PATENT OFFICE

2,672,833

EDGE GUIDE FOR SEWING MACHINES

Herman Ritter, Cranford, N. J., assignor to The Singer Manufacturing Company, Elizabeth, N. J., a corporation of New Jersey

Application February 16, 1951, Serial No. 211,302

8 Claims. (Cl. 112—151)

1

The present invention relates to sewing machines and more particularly to an edge-guide for sewing machines.

The usual sewing machine is provided with a lower four-motion type feed, i. e., the feed-dog traverses a substantially vertical elliptical path, the major axis of which lies substantially parallel to the line of feed. In its feeding movement, the feed-dog projects through the feed-dog slot in the throat-plate and moves forwardly in the direction of feed. The feed-dog then drops below the surface of the throat-plate and is returned in a reverse direction to a point from which it moves upwardly through the throat-plate and again forwardly through another feeding stroke.

During that portion of the feed-cycle in which the feed-dog is moved upwardly through the throat-plate it engages the material being sewed to grip that material against a work-presser commonly in the form of a presser-foot. To insure engagement of sufficient pressure to prevent relative movement between the feed-dog and material, the feed-dog is raised to such an extent that the presser-foot is actually raised from the throat-plate a small amount against the action of a presser-bar spring.

It is desirable, to insure proper functioning of an edge-guide, that the guiding-face of the edge-guide be continually in engagement with the work and the work-supporting bed. Thus, any edge-guide rigid with the usual presser-bar would be impractical since the presser-bar reciprocates vertically during a sewing operation, and the guiding-face of the edge-guide must remain substantially stationary. This can be accomplished only by producing flexing in the shank of the guide, which results in an early breaking of the guide.

It has been suggested to mount the edge-guide on the stationary machine frame. This construction results in undesirable complications due to the fact that the guide should be conveniently movable from operative position to permit the introduction of work into the machine, if the machine is to do other than mere edge-sewing.

It has also been suggested to modify the mounting of the presser-foot upon the presser-bar by introducing a spring-pressed pivot or other equivalent structure so that the presser-bar remains substantially stationary and the movements of the presser-foot are taken upon that pivot. In this construction, the edge-guide can be mounted directly upon the presser-bar. The present invention relates to an improvement in this latter type of edge-guide.

2

The object of the present invention is to provide an improved edge-guide which is inexpensive to manufacture, adapted to be attached to the machine with a minimum of alteration in the machine elements and with a minimum of effort and adjustment to prevent interference with the operation of the machine, and which is readily adapted to perform its intended function.

These and additional objects will be apparent from the following disclosure which sets forth in detail preferred embodiments of the present invention.

Reference is made to the accompanying drawings in which:

15 Fig. 1 is a side elevation view of a presser-foot which carries an edge-guide that embodies the present invention, with fragmentary portions of the sewing machine included to show the relation of the parts.

20 Fig. 2 is an enlarged front elevation view of the presser-foot with the work-supporting surface being shown in section and with a fragmentary portion of the presser-bar included.

Fig. 3 is a perspective view of a presser-foot 25 which carries an edge-guide embodying the present invention.

Fig. 4 is a perspective view of the edge-guide.

Fig. 5 is a view similar to Fig. 2 of a modification of the present invention.

The edge-guide made in accordance with the present invention is particularly adapted for use with a low-inertia presser-foot, although not specifically limited thereto. The presser-foot as shown in the accompanying drawings and described hereinafter is basically the same as that disclosed in my U. S. Patent No. 2,550,499, to which reference is made for a more complete understanding of the present device.

In the drawing there is shown a fragmentary portion of the head 1 of the sewing machine. 40 Journaled therein for endwise reciprocation is a presser-bar 2 and a needle-bar 3. The needle-bar 3 carries at its lower end a needle 4 that is adapted to pierce the work W which is presented to the machine, and to cooperate with a loop-taker (not shown) in the formation of stitches. The work W is advanced past the throat-plate 5 and cloth-plate 6 by a feed-dog 7 which is projected through the usual feed-dog slot 8 in the throat-plate 5. Motion is imparted to the feed-dog 7 by a feed-bar 9 connected thereto and actuated to effect a lower four-motion type feed. The above construction is conventional and will be well understood by those skilled in the art so it is not deemed necessary to expand this disclosure in relation thereto.

The presser-device as disclosed in this preferred embodiment comprises a body-member or shank 10 provided with a socket 11 which is adapted to receive the lower end of the presser-bar 2. The presser-device can be secured to the presser-bar 2 by means of a screw 12 which is threaded into the presser-bar and which projects through an upwardly open slot 13 formed in a wall of the body-member 10 adjacent the socket 11. Referring to Fig. 3, it will be noted that the side walls of the socket 11 are tapered inwardly to facilitate positioning and tightening the presser-device on the presser-bar 2.

The body-member 10 of the presser-device is formed with an integral cylindrical extension 14 provided with external threads 15 adapted to receive a knurled cap-nut 16. A bore 17 is formed in the body-member 10 and extension 14, and disposed therein is a compression spring 18 abutting against the adjustable cap-nut 16 at one end and a plunger 19 at the other. The plunger 19 is slidably mounted in the lower end of the bore 17 and rotatably carries a transverse pin 20 that projects through slots 21 formed in the opposite faces of the body-member 10; the slots 21 being elongated to extend lengthwise of the bore 17. The outer ends of the pin 20 are secured to the upstanding side-plates 22 and 23 of a bifurcated sole-plate 24. This construction provides a low inertia presser-foot in which the sole-plate 24 can move independently of the body-member 10 and presser-bar 2 in response to the rising and falling movements of the feed-dog and the usual variations in the thickness of the work. Reference is again made to the aforementioned U. S. Patent No. 2,550,499 for a more complete understanding of the structure, function and advantages of this construction.

The edge-guide, in accordance with the present disclosure, is formed from a single sheet-metal blank and comprises a shank-portion 25 bent intermediate its ends at substantially a right angle to provide a vertical leg 26 and a horizontal leg 27. It will be readily understood that the legs 26 and 27 need not be exactly vertical and horizontal, respectively, but may vary considerably therefrom without departing from the scope of the present invention. At its extreme upper end, the vertical leg 26 merges into a lateral projection 28 providing a positioning-face 29 located in the plane of the vertical leg. Adjacent the positioning-face 29, there is provided a rearwardly extending apertured ear 30 bent at substantially a right angle along a vertical line to the vertical leg 26. A screw 31 passes through the apertured ear 30 and is threaded into the side of the body-member 10 to secure the edge-guide thereto. The face 29 abuts against the front vertical wall of the body-member 10 to restrain the edge-guide against clockwise rotation about the screw 31. A guide-fin 32, having a work-guiding face, is bent downwardly from the horizontal leg 27 at a right angle into a vertical plane parallel to the direction of feed, and projects through a slot 33 formed in one of the tines of the bifurcated sole-plate 24 to rest upon the throat-plate 5 and to form an abutment against which the work is guided.

The shank-portion 25 of the edge-guide is flexible and spring-like in character so that, when the presser-bar is in its lowered or operative position, the lower edge of the guide-fin 32 is resiliently urged into engagement with the work-support. It should also be noted that the

guide-fin is of such a vertical height that the sole-plate 24, in its normal rising and falling movements, will not contact that portion of the shank 25 which connects with the guide-fin and thus tend to move the guide-fin vertically from the work-support. By this construction, the guide-fin 32 is positively held in engagement with the work-support and is not likely to become disengaged, thereby maintaining control of the edge of the fabric being guided.

In Fig. 5 there is shown an edge-guide similar to the one above described but differing therefrom in its connection to the body-member 10 of the presser-device. In this figure the elements common to those in the device above described carry corresponding numerals. It will be noted in this device that the lateral projection 28' has been modified by being enlarged and apertured to receive the screw 31' which secures the edge-guide to the presser-device, and that the apertured ear 30 has been omitted. Rotation of the edge-guide about the screw 31' is precluded by engagement of the guide-fin 32 with the outer wall of the slot 33 in the sole-plate 24. This is also true to a lesser extent in the device of Figs. 1-4.

In the present devices, which constitute preferred embodiments of the invention, the edge-guide can be applied to the presser-device with a minimum of alteration of that presser-device, namely, the slotted sole-plate and threaded recess in the shank to receive the screws 31 and 31'. It will also be noted that fixing the edge-guide to the presser-device does not require much care to avoid misaligning it in such a fashion as to prevent it from functioning properly or to get it in the path of movement of the needle, but rather, it can be accurately and quickly positioned on the presser-device and secured thereto merely by manipulation of the screw 31 or 31'.

Various changes and further modifications will suggest themselves to those skilled in the art. For example, the slot 33 in the sole-plate 24 may be omitted, and the guide-fin 32 may project through and abut against the needle-slot in the bifurcated sole-plate; or the needle-slot in the sole-plate may be reduced to a needle-aperture, as is common. All such modifications as come within the spirit of this invention are intended to be included within the purview of the appended claims.

Having thus set forth the nature of the invention, what I claim herein is:

1. An edge-guide for sewing machines formed from a single blank of spring-like sheet metal comprising a shank-portion, a guide-fin projecting downwardly from one side edge of one end of said shank-portion, a positioning-face projecting laterally from and substantially in the plane of the other end of said shank-portion on the same side edge thereof as said guide-fin, and an apertured ear projecting rearwardly from the side edge of said shank-portion adjacent to and spaced inwardly from the outer end of said positioning face and lying in a plane substantially at a right angle to the plane of said shank-portion, said apertured ear being adapted to receive securing means for the edge-guide.

2. An edge guide for a sewing machine in accordance with claim 1, in which said shank-portion includes two leg portions arranged at substantially a right angle to each other with said guide-fin carried by one of said legs and said positioning face and apertured ear projecting from the other of said legs.

3. A combined presser-device and edge-guide for sewing machines, comprising a presser-foot having a shank and a work-engaging sole-plate means for mounting said sole-plate upon said shank for pivotal movement about an axis extending widthwise of said sole-plate and for bodily movement with respect to said shank and in a direction transverse to the plane of the work-engaging face of said sole-plate, an edge-guide comprising a work-edge guiding fin extending lengthwise of said sole-plate and intersecting the plane of said work-engaging face, and a resilient fin-supporting member secured to said shank and yieldingly biasing said fin for movement edge-wise relatively to said sole-plate.

4. A combined presser-device and edge-guide for sewing machines, comprising a presser-foot having a shank and a work-engaging sole-plate means for mounting said sole-plate upon said shank for pivotal movement about an axis extending widthwise of said sole-plate and for bodily movement with respect to said shank and in a direction transverse to the plane of the work-engaging face of said sole-plate, and an edge-guide mounted upon said presser shank and having a resilient shank-portion, a guide-fin depending from said shank-portion of said edge-guide and resiliently urged toward the plane of said sole-plate, a positioning-face projecting laterally from the upper end of and in the plane of said shank-portion of said edge-guide, and means for securing said edge-guide to the shank of said presser-device.

5. A combined presser-device and edge-guide for sewing machines in accordance with claim 4, in which said last-mentioned means comprises an apertured ear projecting rearwardly from said shank-portion of said edge-guide adjacent to but spaced inwardly from the outer end of said positioning-face and lying in a plane substantially at a right angle to the plane of said shank-portion, said apertured ear being adapted to receive means to secure the edge-guide to the shank of said presser-device.

6. A combined presser-device and edge-guide for sewing machines in accordance with claim 4, in which said positioning-face is apertured and said last-mentioned means comprises securing means adapted to be received within the aperture of said positioning-face for securing the edge-guide to the shank of said presser-device.

7. In a sewing machine having a work-support and a work-advancing feed-dog operating through said work-support, a combined presser and edge-guiding device comprising a presser-foot shank, a work-engaging sole-plate means for mounting said sole-plate upon said presser-foot shank for bodily movements relative to said shank toward and from said work-support in response to the work-advancing movements of said feed-dog, and a member mounted upon said presser-foot shank and having a work-edge guiding fin biased into engagement with said work-support adjacent said feed-dog, in the operative position of said presser-device.

15 8. In a sewing machine having a work-support and a work-advancing feed-dog operating through said work-support, a combined presser and edge-guiding device comprising a presser-foot shank, a work-engaging sole-plate, sole-plate mounting means upon said shank including a pivotal support providing for rocking movement of said sole-plate about a pivot-axis substantially transverse to the line of feed of the work and supporting means for said pivotal support providing for movement of said pivot-axis toward and from said work-support, spring means yieldingly biasing said pivot-axis toward said work-support, whereby said sole-plate will move bodily relative to said shank responsive to the work-advancing movements of said feed-dog, and a member mounted upon said presser-foot shank and having a work-guiding fin depressed into engagement with said work-support adjacent said feed-dog.
